UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

SHOE AND THE MANUFACTURE THEREOF

Application filed November 23, 1929. Serial No. 409,392.

This invention relates to improvements in the manufacture of shoes and particularly to improvements in the insertion of fastenings adapted but not necessarily limited to use in the manufacture of shoes.

Fibre or paper pegs, as disclosed in Letters Patent of the United States No. 1,729,169, granted September 24, 1929, on an application filed in the name of the present inventor, are being used to a large extent in the manufacture of shoes. These fastenings hold with remarkable tenacity when driven into leather or other suitable material of any substantial thickness. When driven into the very thin material such as that used for the insoles of flexible McKay shoes, particularly those of the cheaper grades, however, they cannot always be relied upon to hold, particularly if there is some variation in the thickness of the layers of stock which are being attached to the thin piece so that some of the fastenings, all of which in this work are ordinarily of the same length, do not pass entirely through the thin layer.

It is an object of the present invention to provide an improved method of inserting pegs, applicable though not limited to the securing of the overlasted marginal portions of shoe uppers to light and thin insoles, which will insure firm anchoring of the pegs even though the substance of the insole stock may be so thin and flimsy that heretofore clenched metallic fastenings would have been necessary. In accordance with the method of the present invention as herein exemplified I obtain this result by securing a sheet of stiff material, such as fibre board, to the material of the insole at the side thereof adjacent to the shoe upper and, by forming a fastening receiving hole in the layers of the material, form a burr from the fibre board or other stiff material which, when a paper or fibre peg is driven into the material, firmly grips the peg and prevents it from being pulled out.

In another of its aspects the invention comprises an improved shoe or other article layers of which are secured together by a paper or fibre peg or pegs passing through a sheet of stiff fibre board or analogous material secured to one of the layers and between that layer

and another layer, the pegs being held against withdrawal by burrs formed from the fibre board.

With the above and other objects in view the invention will now be described in connection with the drawings which illustrate the forward portion of a shoe the upper of which is secured in lasted relation to the insole by fastenings inserted in accordance with my invention, and will be pointed out in the claims.

In the drawings,

Fig. 1 is a perspective view of the forepart of the shoe positioned bottom upwardly, the upper being secured in lasted relation to the insole at the toe portion of the shoe by fastenings inserted in accordance with this invention;

Fig. 2 is a perspective view of the forward and shank portions of an insole having a thin sheet of fibre board secured to its toe portion in order to anchor fastenings thereto;

Fig. 3 is a longitudinal sectional view on an enlarged scale through a portion of a shoe lasted as in Fig. 1, during the performance of the lasting operation, and showing the awl of a fastening inserting implement at a time when it has passed through the layers and substantially contacts with the metal bottom plate of the last; and

Fig. 4 is a longitudinal sectional view through the toe of the shoe of Fig. 1, on the same scale as Fig. 3, showing a fastening which has just been inserted by the driver of a fastening inserting implement.

The invention is illustrated and described herein with reference to the lasting of a McKay shoe 10 the marginal portion 14 of the upper 16 of which is secured in lasted relation to an insole 18, from substantially the tip line rearwardly to the heel breast line by staples 20 which are deflected as they enter the stock so that they are anchored in the insole, as disclosed, for example, in an application for Letters Patent of the United States Serial No. 209,299, filed July 29, 1927 in the name of George Goddu.

The toe end of the shoe upper, and the heel portion also if desired, is secured in lasted relation to the insole 18 by paper or fibre pegs

22 of the nature disclosed in the above-mentioned Letters Patent of the United States No. 1,729,169, inserted, for example, by an implement of the character disclosed in my co-pending application for Letters Patent of the United States, Serial No. 350,901, filed March 29, 1929. Such an implement is provided with a nozzle 24 (Figs. 3 and 4) and a tool 26 which acts both as an awl and as a driver.

10 In order to insure that the pegs 22 will hold in the insole 18, even though the latter be of thin and relatively flimsy material such as a cheap leather split of two irons or thereabouts (one iron equals 1/48th of an inch) in thickness, a sheet of hard stiff material such as fibre board 28 is secured, for example by a suitable adhesive, to the insole 18. The insole is mounted on a last 30 (Figs. 3 and 4) having the usual bottom plate 32 with which last of the type used in making McKay shoes are provided. After the side lasting has been performed in the manner mentioned above or in any other suitable way the material is worked into lasted position at the ends of the shoe, for example by a bed lasting machine, and is secured to the insole 18 by the pegs 22. When the nozzle 24 of the fastening inserting implement is pressed against a portion of the shoe upper which has been worked into lasted relation to the insole and the implement is operated to insert a fastening, the tool 26, acting as an awl, is forced downwardly, passing through the layers of the shoe upper, as illustrated the upper leather 34, the doubler 36, box toe 38 and the lining 40. The tool 26 then passes through the fibre board 28 and the insole 18, burring the fibre board as shown at 42 in Fig. 3. Then the tool 26 is withdrawn and, after the peg 22 has been brought into the nozzle 24, the tool 26 is operated, acting as a driver to insert the peg 22, as shown in Fig. 4. It will be observed that the peg 22 completely fills the hole formed by the tool 26 in the layers of stock and that any tendency to withdraw the peg tends to return the burred portion 42 of the fibre board 28 toward its original position thus gripping the peg even more firmly and effectively preventing its withdrawal under any ordinary stresses. As the sheet 28 of the fibre board is secured firmly to the insole 18 a firm anchorage for the pegs is obtained even though the insole 18 may be inadequate, by reason of its thickness or consistency, if it alone were relied upon to hold the pegs.

60 If desired, and as illustrated in Fig. 4, the pegs may be somewhat longer than the thickness of the layers into which they are inserted so that they will be headed at their upper ends. This will effectively prevent the layers of the stock from pulling off over the head ends of the pegs.

65 While the invention has been illustrated

herein with reference to the lasting of shoes it should be understood that in various of its aspects it is not limited to use in that relation. Obviously it may be used for other purposes not necessarily relating to the manufacture of 70

Having thus described my invention what I claim as new and desire to secure by Letters Patent of the United States is:

1. That improvement in methods of inserting paper pegs which comprises forming a hole through a layer of sheet material and a reinforcing sheet of stiff fibre board secured thereto and thereby forming a burr from the fibre board, and driving a paper peg into the material, whereby the paper peg is firmly gripped by said burr. 75

2. That improvement in methods of inserting paper pegs which comprises forming a hole through two or more layers of sheet material and a reinforcing sheet of stiff fibre board secured to one of the layers, and driving a paper peg into the hole formed in the layers of material and the fibre board, whereby the paper peg is firmly gripped by a burr formed from the reinforcing fibre board. 80

3. That improvement in methods of inserting paper pegs which comprises forming a hole through two or more layers of sheet material, and a sheet of stiff fibre board secured to one of said layers at the side thereof adjacent to another of the layers, and driving a paper peg into the layers of material, whereby the paper peg is firmly gripped by a burr formed from the reinforcing fibre board. 85

4. That improvement in methods of manufacturing shoes which comprises reinforcing a thin insole with a thin sheet of stiff material, positioning a shoe part which is to be secured to the insole in the desired relation thereto, and forming a hole through said shoe part, the reinforced material and the insole, thereby forming a burr projecting from the sheet of reinforcing material, and driving a peg into the hole, whereby the peg is firmly gripped by the burr formed from the reinforcing material. 95

5. That improvement in methods of manufacturing shoes which comprises reinforcing a thin insole with a thin sheet of stiff fibre board, positioning a shoe part which is to be secured to the insole in the desired relation thereto, stabbing a hole through said shoe part, the reinforcing fibre board and the insole, thereby forming a burr projecting from the sheet of fibre material, and driving a paper peg into the hole, whereby the peg is firmly gripped by the burr formed from the reinforcing fibre board. 100

6. That improvement in methods of lasting shoes which comprises working a portion of a shoe upper into lasted relation to an insole which is reinforced with a thin sheet of stiff material, forming holes through the layers of the shoe upper, the stiff reinforcing mate- 115

rial and the insole, and driving fibre pegs into the holes, the forming of the holes through the stiff material burring that material and causing it firmly to grip the pegs when they are inserted.

5 7. That improvement in methods of lasting shoes which comprises working the end portion of a shoe upper into lasted relation to an insole the corresponding end portion of which is reinforced with a sheet of stiff material, forming holes through layers of the shoe upper, the reinforcing material and the insole, and driving fibre pegs into the holes, the forming of the holes through the stiff reinforcing material burring the said material and causing it firmly to grip the pegs when they are inserted.

10 8. That improvement in methods of lasting shoes which comprises working the toe portion of a shoe upper into lasted relation to an insole the toe portion of which is reinforced with a sheet of hard fibre board, forming holes through the layers of the shoe upper, the reinforcing fibre board, and the insole, and driving paper pegs into the holes, the forming of the holes through the fibre board burring the fibre board and causing it firmly to grip the pegs when they are inserted.

15 9. An article of manufacture comprising a plurality of layers of stock secured together by a fibre peg which passes through a sheet of relatively hard stiff material positioned between the layers of stock and secured to one of them, the hard stiff material being burred where the peg passes through and thereby firmly gripping the peg and holding it against withdrawal.

20 10. A shoe the upper of which is secured in lasted relation to the insole by fibre pegs inserted through the layers of the shoe upper into the insole, the fibre pegs also passing through a sheet of relatively hard and stiff material positioned between the marginal portion of the upper and the insole and secured to the insole, the hard and stiff material being burred where the pegs pass through and thereby firmly gripping the pegs.

25 11. A shoe the upper of which is secured in lasted relation to the insole by fibre pegs inserted through the layers of the shoe upper into the insole, the fibre pegs also passing through a sheet of hard fibre board positioned between the upper and the insole and secured to the insole, the fibre being burred where the pegs pass through and thereby firmly gripping the peg.

30 12. A shoe the upper of which is secured in lasted relation to the insole by paper pegs inserted through the layers of the shoe upper into the insole, the paper pegs also passing through a sheet of hard fibre board positioned between the marginal portion of the upper and the insole and secured to the insole by adhesive, the fibre board being burred

where the pegs pass through and thereby firmly gripping the peg.

In testimony whereof I have signed my name to this specification.

FRED N. LA CHAPELLE.
